SHOE WITH ELASTIC WEBBING AND LOOP
THEREOVER

Joseph H. Everston, Los Angeles, Calif.

Application September 2, 1948, Serial No. 47,373

11 Claims. (Cl. 36—8.5)

1

This invention relates to a shoe with elastic webbing connecting the quarters at the rear and concealed by a loop of a strap passing over the webbing and free of the quarters at the top of the shoe.

The present application is a companion to my application entitled Shoe With Sole Stay Extension, filed November 14, 1947, Serial No. 785,877, now abandoned. It is the object of the present invention to provide a highly flexible shoe construction in which the quarters are not directly connected but are yieldably connected by means of elastic webbing or the like, it being a major purpose of the invention to conceal the webbing so that its presence is not apparent in the shoe, its action, however, being unimpaired.

In the past, the use of goring has been objectionable because of its appearance, and also because the rubbing of exposed goring against the wearer's foot and stocking has caused abrasion and wear. According to the present invention, a loop is provided free of direct connection with the upper margins of the quarters, through which loop the elastic goring not only functions smoothly, as in a fabricated runway, but remains invisible and protected from contact with hosiery or ankles of the wearer. The seams binding the goring to the edges of the upper at the top of the shoe are likewise concealed and protected.

Yet, in accordance with a major purpose of the present invention, the construction provides a unique combination of vertical support and lateral stretch. Vertical support is obtained by reason of a tongue carried upwardly from the outsole to protect the heel and serve as a backstay. While it may extend the full height of the shoe, it is properly left free of the upper at the top of the shoe to permit of the lateral yielding which is an important feature of the present invention. If the tongue or stay were bound stiffly to the ankle of the wearer at the top of the shoe, it would undesirably function as a splint or brace. Instead, it simply acts as a high counter, so shaped as to afford correct tread and proper foot balance.

Despite the presence of the stay or vertical reinforcement, great elasticity in a lateral direction is afforded by the goring. A child's foot, in particular, is soft, tender and plastic. In a tightly laced shoe of conventional design, there is no room for ankle movement or expansion. The result is cramping of the muscle and tissue, with consequent impedance of circulation and ugly red marks around the ankle. In the use of the present invention, the goring permits the shoe to

stretch or expand or distort as the ankle moves or expands. The shoe yields with every movement of the bones or muscles above the heel bone. The shoe may be laced snugly without unduly binding the foot.

It is a further object of the invention to provide for incorporating the advantages hereof in shoes of various types and constructions as will hereinafter be more fully disclosed.

10 In the drawings:

Figure 1 is a rear quarter view in perspective of a child's shoe embodying my invention.

Figure 2 is a view similar to Fig. 1 showing some of the parts of the shoe prior to their final connection.

Figure 3 is a view similar to Fig. 1 showing the various components of the parts of the shoe as they appear partially separated and prior to connection.

20 Figure 4 is a view in transverse section fragmentarily illustrating a rear portion of the finished shoe.

Figure 5 is a view in vertical longitudinal section fragmentarily illustrating a rear portion of the finished shoe.

25 Figure 6 is a view similar to Fig. 3 illustrating a modified embodiment of the invention.

Figure 7 is a view in perspective fragmentarily showing the assembly of parts illustrated in Fig. 30 6 as viewed from the front.

Figure 8 is a fragmentary detail view in horizontal section on line 8—8 of Fig. 9.

Figure 9 is a fragmentary detail view in vertical section on line 9—9 of Fig. 8.

35 Figures 10 and 11 are views similar to Fig. 9 and respectively illustrating further modified embodiments of the invention.

Figure 12 is a fragmentary detailed view of the rear portion of a shoe, portions thereof being 40 broken away to illustrate a further modified embodiment.

Figure 13 is a fragmentary detailed view in vertical longitudinal section through the shoe of Figure 12.

45 In the construction shown in Figures 1 to 5, the invention is illustrated as embodied in a children's shoe, it being particularly adapted for that purpose although not all confined to children's shoes.

As in the shoe of the companion application 50 above identified, the outsole 15 is provided with an upwardly extending tongue 16 which, in this instance, leads up the back of the shoe to a point slightly higher than the top margins 17, 18, of the respective quarters 19, 20. The rest of the upper 55 is conventional and needs no description here.

The insole 21 is provided with a similar upwardly extending tongue 22 which lies at the outside of the quarters for a portion of the height of the shoe, being then shouldered at 23 as best shown in Figures 2 and 3. Above the shoulders 23 the tongue is provided with a strap-like extension at 24.

The upper is flanged outwardly at 25 throughout its lower perimeter, the flange extending part way up the rear margins of the quarters 19 and 20 to substantially the level of the shoulders 23 of the insole tongue 22. The quarters are nowhere connected directly with each other. Below the point where the flange 25 ends at the rear of the shoe the quarters are connected by their stitched attachment to the intervening tongues 16 and 22 of the outsole and insole. Above shoulders 23, a piece of webbing 26 is inserted, elastic webbing being preferably used in order to provide yielding between the quarters at the top of the shoe where the child's ankle requires freedom of movement. This webbing is stitched to the quarters along the spaced margins 21, 28 thereof, the same stitching being desirably used to hold the top facing 29, 30.

In assembling the shoe, the insole 21 is first connected with the outwardly turned flange 25 of the upper by an inner row of stitching 31 (Fig. 1). This row of stitching ends where the shoulders 23 of the insole tongue 22 register with the ends of the flange 25 at the rear of the shoe. The tongue extension 24 is tucked between the quarters to lie inside of the webbing 26 as shown in Fig. 2.

The outsole is next applied by means of a second or outer row of stitching 33 (Fig. 1), which likewise extends the whole length of the flange 25 and terminates at the end of the flange where the shoulders 23 of the insole tongue 22 register with such ends. The terminal strap portion 35 of the outsole tongue 16 is thus left free of connection with the upper and projects beyond the top of the shoe and overlaps laterally the margins 27, 28, of the respecting quarters. The top ends of the strap extension 24 of the insole and the free terminal strap portion 35 of the outsole tongue 16 are now connected by a row of stitches shown at 36 in Fig. 1, this row of stitches being free of all contact with the upper or with the webbing and extending over the upper margin of the webbing insert to provide a loop which completely conceals the webbing while leaving the webbing free to yield, whereby to provide resilient connection between the quarters at the top rear of the shoe.

The construction shown in Figures 6, 7, 8 and 9 is similar to that already described except that the insole tongue 226 has marginal portions 227, 228 stitched to the outsole strap 356 throughout the height thereof. The insole tongue extension 246 is cut from between the marginal portions 227 and 228 upon rearwardly converging lines as shown in Fig. 8, leaving skived or beveled margins forming oblique slots through which the elastic webbing 266 extends to connect the quarters, which are otherwise free above the level where flange 25 ends (Fig. 6). The insole tongue extension 246 is stitched transversely at 247 to the tops of outsole strap extension 356 and insole tongue portions 227 and 228 to complete the loop through which the webbing operates.

A vertical line of stitching at 248 (Figures 7 and 8) may connect the vertical center lines of the insole tongue extension 246 through the webbing 266 to the outsole tongue extension 356, this

feature being optional and of course, usable not only in this embodiment but in the others as well. Where used it keeps the webbing centered and holds the loop flat. Yet the quarters can yield oppositely with freedom.

In the construction shown in Fig. 10, the insole tongue is wholly omitted, the loop which conceals the webbing insert at 26 being provided by an integral strap 38 of the outsole tongue 162 folded at 352 over the top of the webbing.

Whereas Figure 10 shows the loop entirely made of component strap-like parts of the outsole tongue, Figure 11 shows how the same result is achieved by making the loop entirely from 15 component strap-like extension parts of the insole tongue. In this case the insole tongue 223 has its strap extension 243 folded back upon itself at 353 and thence carried downwardly at 39 outside of and behind the elastic webbing insert 26 and stitched at 40 to the upper end of the relatively shorter outsole tongue 163.

The loop which conceals the elastic webbing insert may also be fabricated separately from either the outsole tongue or the insole tongue and to illustrate this point, and at the same time to show 25 how the invention may be embodied in shoes other than children's shoes, I have illustrated in Figures 12 and 13 a conventional Goodyear welt shoe with a heel at 41 supporting the outsole 154. Behind the counter, 43, for a portion of the height of the shoe, the quarters 194 and 204 are joined by a rear seam 44 which terminates where the quarters are shouldered at 45 (Fig. 12) to receive the elastic webbing insert 26 just as above 30 described. At this level, stitching 42 connects the short insole tongue 224 with the quarters at the top of the counter 43. The same stitching may extend through the finishing strap 50 which covers seam 44 and is stitched at 46 and 35 47 to the respective quarters. Above the level of the seam at 42 the strap is free of all connection with the quarters to provide the desired loop at 48 to conceal the webbing insert 26 while leaving it free for elastic connection of the quarters. On the inside of the shoe the strap 50 may 40 terminate at the level of the stitching 45, this being at the bottom of the loop 48.

In similar manner, the invention may be adapted for use in shoes of any construction, it being necessary only to separate the quarters at 50 the top rear of the shoe and insert elastic webbing or the like, thereupon concealing the webbing either by means of a strap extending from one of the soles, or by means of a separately applied strap, so connected, in any case, as not to interfere with the free expansion and contraction 55 of the webbing which it conceals within its loop formed over the top rear margin of the shoe.

I claim:

60 1. In a shoe, the combination with an upper having portions spaced laterally at their top margins at the rear of the shoe, and a backstay providing a relatively unyielding reinforcement of the upper and connected with the upper for 65 only a part of the height thereof below the top margins of said laterally spaced upper portions, and elastically expansible means fastened to such laterally spaced portions only above the said connection of the upper with the backstay, 70 said back stay having associated therewith means forming a loop disposed over said elastically expansible means, said loop being marginally free of said upper portions and having at least its external part lapping said portion and covering 75 said means for the concealment thereof

while permitting freedom of expansion and contraction of such means.

2. The device of claim 1 in which said backstay comprises an outsole tongue extending above the uppermost point of connection of said backstay with said upper, the external part of the loop comprising an extension of said tongue.

3. The shoe of claim 1 in which the said loop is formed in part by an insole tongue folded over the expansible means and connected to the backstay.

4. The shoe of claim 1 in which the said loop is formed in part by a tongue constituting an extension of the backstay and in part by a tongue constituting an extension of the insole respectively connected with the quarters of the shoe below said means and the said connection between the internal and external parts of the loop is independent of the quarters and above said means.

5. The shoe of claim 1 in which said loop is formed in part by an extension of the back stay which is folded upon itself to extend over the top of the shoe about said elastically expansible means and connected below said means with said shoe.

6. A shoe comprising an upper having quarters with portions spaced adjacent the top rear of the shoe, elastic webbing connecting said spaced portions, relatively inelastic backstay means connected to said quarters below said webbing, and a loop wider than the space between the quarter portions and spanning the top of said shoe across said webbing in concealing relation thereto and having interior portions connected with said quarters below said webbing and exterior portions connected with the backstay means.

7. A shoe comprising an upper having quarters with portions spaced adjacent the top rear of the shoe, elastic webbing connecting said spaced portions, relatively inelastic back stay means connected to said quarters below said webbing, and a loop wider than the space between the quarter portions and spanning the top of said shoe across said webbing in concealing relation thereto and having interior portions connected with said quarters below said webbing and exterior portions connected with the back stay means, said shoe having an outsole of which said backstay means constitutes an upward extension at the rear of the shoe, the said quarters having flanges to which said extension is marginally connected below the webbing.

8. A shoe comprising an upper having quarters with portions spaced adjacent the top rear of the shoe, elastic webbing connecting said spaced portions, relatively inelastic back stay means connected to said quarters below said webbing,

and a loop wider than the space between the quarter portions and spanning the top of said shoe across said webbing in concealing relation thereto and having interior portions connected with said quarters below said webbing and exterior portions connected with the back stay means, said shoe having marginal flanges on said quarters and having an insole marginally connected with said flanges and extending upwardly at the rear of the shoe to substantially the level of the webbing, said loop being formed at least in part by an insole tongue passed inwardly of the shoe below the webbing and thence extending upwardly within the shoe free of connection with the quarters.

9. In a shoe, the combination with upper portions spaced laterally and relatively yieldable for a substantial distance below their top margins at the rear of the shoe and provided with a non-yielding connection therebeneath, of an elastically expansible web having lateral margins fastened to said spaced upper portions only above the non-yielding connection, sole means connected with the upper, and a loop comprising parts internally and externally disposed respecting the web and connected over the web, at least the external part of said loop being wider than the space between the yieldable upper portions and lapping said upper portions to conceal the web, both of the parts forming the loop being connected with said upper portions below the level of the web and free of said upper portions where the latter are relatively yieldable to permit free expansion and contraction of the web, said external part comprising a relatively unyielding backstay.

10. The shoe of claim 9 in which the loop is formed in part by a tongue portion of said sole means which forms at least the internal part of the loop.

11. The shoe of claim 9 in which the loop is formed in part by a tongue extension of an element of said sole means.

JOSEPH H. EVERSTON.
